UNITED STATES PATENT OFFICE

FRANK J. ABEL, OF NEW YORK, N. Y., ASSIGNOR TO SUN RISE LAMP MFG. CO., INC., A CORPORATION OF NEW YORK

DESIGN FOR A CLOCK FRAME OR ARTICLE OF ANALOGOUS NATURE

Application filed February 6, 1930. Serial No. 34,444. Term of patent 3½ years.

To all whom it may concern:

Be it known that I, FRANK J. ABEL, a citizen of the United States of America, and a resident of the city of New York, in the county of Bronx and State of New York, have invented a new, original, and ornamental Design for Clock Frames or Articles of Analogous Nature, of which the following is a specification, reference being had to the accompanying drawing, forming a part hereof.

Figure 1 is a front elevational view of the

clock frame or article of analogous nature, the part shown in full line outline being ornamented in the same manner as the part more fully illustrated;

Figure 2 is an end view of the same; and Figure 3 is a top plan view of the same.

I claim:

The ornamental design for a clock frame or article of analogous nature substantially as shown and described.

FRANK J. ABEL.
